EXPENDABLE SHAPED EXPLOSIVE CHARGE
WELL CASING PERFORATING APPARATUS

Glen Reid Hodgson, Houston, Tex., assignor, by mesne assignments, to Borg-Warner Corporation, Chicago, Ill., a corporation of Illinois

Filed Nov. 22, 1952, Ser. No. 322,017

2 Claims. (Cl. 102—20)

The present invention relates to apparatus utilizing shaped explosive charge means in expendable carrier means which is adapted to be lowered into a well on a supporting cable or other suspension means to perforate the well casing, for example. More specifically, it has to do with novel means for completely separating the expendable carrier means from the suspension means upon detonation of the explosive charge means.

In the completion of oil and gas wells, it has become common practice to perforate the well casing to bring a well into production after the small diameter tubing has been set and the production equipment has been installed at the surface. This has been made possible by the recent development of highly effective perforating apparatus which is small enough to pass through the well tubing. As disclosed in the copending application Serial No. 209,598, filed February 6, 1951 by Harry S. Robertson, for "Apparatus for Perforating Well Casing and the Like," now U.S. Patent No. 2,853,944, issued September 30, 1958, such apparatus comprises one or more shaped explosive charge devices mounted in expendable carrier means adapted to be lowered into a well on suspension means. Upon detonation of the charges, the carrier means is destroyed and only the suspension means is brought out of the well. Complete destruction of the carrier means is desirable since if deformed or only partially destroyed portions of the carrier remain attached to the suspension means, it may be difficult to withdraw the latter through the well tubing.

It is an object of the invention, therefore, to provide well casing perforating apparatus of the above character which includes means for positively severing the carrier means from the suspension means therefor without leaving deformed carrier portions on the latter which might make it difficult to withdraw the suspension means through the well tubing upon completion of a perforating operation.

This is accomplished, according to the invention, by placing explosive charge means in juxtaposition to the carrier means near the place where the latter is secured to the suspension means. Upon detonation of the perforating explosive charges, the explosive charge means is detonated to separate the carrier means cleanly from the suspension means. In a preferred embodiment, the explosive means comprises a portion of the detonating fuse for the perforating explosive charges, which may be wrapped around a suitable member in close proximity to the upper end of the carrier means. By virtue of this construction, the separation of the carrier means from its suspension means may be effected in a simple yet highly effective manner.

For a better understanding of the invention, reference is made to the following detailed description of a typical embodiment, taken in conjunction with the single accompanying figure.

In the figure, the shaped charge perforating apparatus 10 may comprise a hollow, imperforate, pressure resilient tube 11 made of any suitable frangible material such as

aluminum, for example, closed at its upper and lower ends by a cable head 12 and a nose plug 13, respectively. The cable head 12, to which the supporting cable 14 is secured, is preferably made of strong material such as steel, for example, so as not to be damaged by the explosive forces developed in a perforating operation. The cable head 12 has a portion 15 of reduced diameter which is adapted to be snugly received within the upper end of the tube 11 and which is weakly secured to the latter by one or more shear pins 16, for example, so as to facilitate separation of the two when the perforating apparatus is fired. Packing means such as one or more O-rings 17 may be disposed in an annular groove 18 formed in the cable head portion 15, to insure watertightness.

Similarly, the nose plug 13 has a portion 19 of reduced diameter which is snugly received within the lower end of the tube 11 and secured thereto by one or more screws 20, for example, one or more O-rings 21 being provided in an annular groove 22 in the nose plug portion 19 to insure a watertight joint.

Within the tube 11 are a plurality of longitudinally spaced apart shaped explosive charge devices 23 which may be mechanically coupled together by cooperating coupling means 24 and 25 with their longitudinal axes at oblique angles to the longitudinal axis of the tube 11, all as explained in the aforementioned Robertson application. The explosive charges in the devices 23 are adapted to be detonated by a Primacord fuse 26 which is threaded through openings 27 at the rear of the explosive charge devices 23, the lower end of the fuse 26 being mechanically coupled to an electric blasting cap 28. One terminal of the blasting cap 28 may be grounded to the nose plug 13 at 29 and its other terminal may be connected by a conductor 30 to a terminal 31 which connects to a conductor 32 in the supporting cable 14 extending to the surface of the earth. The upper end of the conductor 32 is connected in series with a firing switch 33, a rheostat 34 for controlling current intensity, and a source of electrical energy 35, the other end of which is grounded at 36.

In accordance with the invention, the upper end of the Primacord fuse 26 is wound in the form of a helical coil 26a of several turns having substantially the same outer diameter as the inside diameter of the tube 11, any suitable means such as friction tape (not shown), for example, being used to hold it in shape. A tubular member 37 of substantially the same outer diameter as the inner diameter of the coil 26a is then inserted within the coil 26a and the coil 26a and member 37 are inserted in the upper end of the tube 11 as shown in the figure.

In operation, the apparatus 10 is lowered into a well and is brought to rest at the level therein where a perforating operation is to be made. The switch 33 is then closed, detonating the explosive charges in the devices 23 and perforating the surrounding earth formations. Simultaneously, the detonation of the portion of the fuse 26 wrapped around the member 37 completely destroys the upper end of the tube 11 and leaves no parts thereof attached to the cable head 12 so that the latter can readily be withdrawn through the narrow diameter tubing in the well. The member 37 aids in directing the forces developed upon detonation of the fuse 26 outwardly against the upper end of the tube 11.

The invention thus provides novel means for insuring the complete separation of the cable head from the rest of the apparatus upon detonation of the explosive charges therein. By employing weak securing means to secure the cable head to the carrier means and by detonating a coiled portion of the detonating fuse for the perforating charges in close proximity to the carrier means near the place where it is connected to the cable head, the car-

rier means may be cleanly separated from the cable head in a simple and effective manner.

It will be understood that the representative embodiment described herein is susceptible of modification within the spirit of the invention. For example, the tubular member 37 might be eliminated. Also, the return circuit to the perforator apparatus in the well may be through the earth or through the metal armor of the cable 14. Similarly, the helical coil of Primacord fuse may be replaced by an explosive charge of adequate shape, for example a circular ring, adapted to be ignited by the Primacord fuse 26. Further, the apparatus may be used in conjunction with a casing collar locator of the type shown in Fagan Patent No. 2,558,427 located in an extension of cable head 10 (not shown). The single embodiment disclosed, therefore, is to be regarded merely as illustrative of the invention and not as limiting the scope of the appended claims.

I claim:

1. In apparatus for perforating well casing and the like, the combination of an elongated expendable, relatively thin-walled tube providing a hollow interior of a size to receive shaped explosive devices, said tube having a closure member for the lower end thereof, a non-expendable head member weakly secured to the upper end of said tube and forming a closure therefor, suspension means connected to said head member for suspending the apparatus in a well, a plurality of longitudinally spaced apart shaped explosive devices disposed in the hollow interior of said tube, a rigid member mounted in the upper end of said tube, said member being spaced from the inside wall of said tube to provide with the latter an annular space, a flexible detonating fuse having portions disposed adjacent the rear ends of said explosive devices and having an end portion disposed circumferentially in the space between said rigid member and the inside wall of said tube in close proximity to said inside wall, said fuse end portion being capable of severing said tube from said head member, and means for initiating detonation of said fuse from the surface of the earth, whereby the body of said expendable tube and the contents thereof will be destroyed upon detonation of said

charges and the tube will be cleanly separated from the head member.

2. In apparatus for perforating well casing and the like, the combination of an elongated expendable, relatively thin-walled tube providing a hollow interior of a size to receive shaped explosive devices, said tube having a closure member for the lower end thereof, a non-expendable head member having a portion extending into the upper end of said tube in fluid-tight telescopic relation thereto, means including a shearable element weakly securing said tube to said extending portion of said head member, said head member forming a closure for said tube, suspension means connected to said head member for suspending the apparatus in a well, a plurality of longitudinally spaced apart explosive devices disposed in the hollow interior of said tube, a rigid member mounted in the upper end of said tube, said member being spaced from the inside wall of said tube to provide with the latter an annular space, a flexible detonating fuse having portions adjacent the rear ends of said explosive devices and having an end portion disposed circumferentially in the space between said rigid member and the inside wall of said tube in close proximity to said inside wall, said fuse end portion being capable of severing said tube from said head member, and means for initiating detonation of said fuse from the surface of the earth, whereby the body of said expendable tube and the contents thereof will be destroyed upon detonation of said charges and the tube will be cleanly separated from the head member.
